UNITED STATES PATENT OFFICE.

HERBERT M. DAWLEY, OF BUFFALO, NEW YORK, ASSIGNOR TO THE PIERCE-ARROW MOTOR CAR COMPANY, OF BUFFALO, NEW YORK.

DESIGN FOR A MOTOR-VEHICLE BODY.

45,185.

Specification for Design.

Patented Feb. 3, 1914.

Application filed December 21, 1912. Serial No. 738,075. Term of patent 14 years.

To all whom it may concern:

Be it known that I, HERBERT M. DAWLEY, a citizen of the United States, residing at Buffalo, in the county of Erie and State of New York, have invented a new, original, and ornamental Design for Motor-Vehicle Bodies, of which the following is a specification.

The accompanying drawing is a perspective view of a motor vehicle body showing the design.

The characteristic feature of this design consists in the relatively short cape top A

which terminates at its front end at a point in rear of the front end of the body B of the vehicle, and the windows C, D, in rear of the driver's seat E between the top A and the body B of the vehicle.

I claim:

The ornamental design for a motor vehicle body, as shown and described.

HERBERT M. DAWLEY.
